UNITED STATES PATENT OFFICE.

HOLMES IVES, OF CHIPPEWA FALLS, WISCONSIN.

DESIGN FOR A TIRE-TREAD.

54,551.

Specification for Design.

Patented Mar. 2, 1920.

Application filed September 3, 1919. Serial No. 321,470. Term of patent 14 years.

To all whom it may concern:

Be it known that I, HOLMES IVES, a citizen of the United States, residing at Chippewa Falls, in the county of Chippewa and State of Wisconsin, have invented a new, original, and ornamental Design for Tire-Treads, of which the following is a specification, reference being had to the accompanying drawings, forming part thereof.

Figure 1 is a top-plan view of a portion of a tire.

Fig. 2 is a cross-section of the tire taken on line 2—2 of Fig. 1.

I claim:

The ornamental design for a tire tread, as shown.

HOLMES IVES.
